SEALING CLOSURE FOR BOTTLES

Murray Kay, New York, N. Y., assignor to Steel
Band Closure Co., Inc., New York, N. Y., a cor-
poration of New York

Application May 9, 1934, Serial No. 724,642

14 Claims. (Cl. 215—95)

This invention relates to improvements in bottle seals and has for its object to provide a simple, inexpensive and practical device of this character which will prevent tampering with the contents of the bottle from the time the bottle leaves the bottling establishment until it reaches the consumer. A further object of the invention is to provide a device of this character which will, in part, remain permanently associated with the bottle in such manner that the bottle cannot be refilled with a substitute of the original product and sold to the purchaser as the genuine article.

Other objects as well as the novel details of the construction of a bottle seal embodying the invention will become apparent after a consideration of the description hereinbelow set forth taken in conjunction with the accompanying drawing in which similar reference characters identify similar parts in the several views and in which Fig. 1 shows in elevation the top portion of a bottle provided with a seal made in accordance with the invention; Fig. 2 is a central vertical section thereof taken along the line 2—2 of Fig. 1; Fig. 3 is a horizontal section taken along the line 3—3 of Fig. 2; Fig. 4 shows in elevation the top portion of a bottle embodying a modified form of the invention; Fig. 5 is a central vertical section of the seal shown in Fig. 4; and Fig. 6 is a horizontal section taken along line 6—6 of Fig. 4.

Referring more particularly to Figs. 1, 2 and 3 of the drawing, the reference character 1 designates the neck of a bottle which is provided with a seal made in accordance with the preferred form of the invention. Closely adjacent to the top portion of the neck of the bottle is a relatively deep annular groove 2 formed between the annular beads 3 and 4. The continuity of the groove 2 about the neck of the bottle is broken by a partition of glass 5 which extends transversely across the groove, as shown in Figs. 2 and 3, and is formed integrally with the inner wall of the groove and the beads 3 and 4. The partition of glass 5 is covered over with a slab or knob 6 of glass which spans the annular beads 3 and 4 and is integrally formed with such beads and the partitions 5. The knob of glass 6 is sufficiently wide to arch over a portion of the groove 2 on each side of the partition 5 forming a recess on each side of the glass partition 5.

Covering the top portion of the neck of the bottle and extending below the groove 2 is a destructible sealing element or closure cap 7. The closure cap 7 may be made of cellulose, metal foil, or any other suitable material such as is ordinarily used for this purpose and may be weak-

ened by an annular scoring 8 intermediate the groove 2 and the open end of the bottle so that the top portion thereof may be readily removed to open the bottle.

Seated in the groove 2 and encircling the closure cap 7 is a substantially heavy metal split band or ring 9 of such diameter that it wedges an annular portion of the closure cap 7 tightly against the inner wall of the groove 2. The split ring 9 is of sufficient circumference so that the end portions thereof are contained within the recesses formed on each side of the partition 5, the ends thereof preferably abutting against each side of the partition, as shown in Fig. 3. The ring 9 may be of any desired thickness and may even be of sufficient thickness to protrude beyond the edges of the annular beads 3 and 4. I prefer, however, to make the thickness of the ring less than the depth of the groove 2 formed between the annular beads 3 and 4 so that the ring is entirely contained within such groove. The outer edges 10 and 11 of the ring 9 and the edges 12 and 13 of the beads 3 and 4 respectively are rounded or otherwise suitably shaped so that a chisel or other sharp tool cannot get a purchase on the edges of the ring 9 thereby preventing the removal of the ring from the groove 2 by such means. The width of the ring should be also such that it fits snugly in the groove 2 thereby presenting no space between the sides of the ring and the sides of the beads 3 and 4 whereby a tool might be inserted. The ring is made of a strong, hard metal such as steel. I preferably, however, make the ring out of case-hardened steel which is sufficiently hard and strong to make it exceedingly difficult and impractical to attempt to drill the ring or to pry out the ends of the ring from the recesses on each side of the partition 5. If anyone attempted to pry a ring of this character out of the groove, the force that would be required to accomplish this purpose would be materially greater than the glass in the bottle could stand, so that the glass bottle would unquestionably break. Thus by reason of this construction it is practically impossible to remove the ring 9 from the groove 2 and it is to all practical intents and purposes, a permanent part of the bottle.

Before the closure 7 and the ring 9 are mounted on the neck of the bottle the flanged cork 14 is inserted in place, the flanged top thereof seating on the top of the bottle in the usual manner. The closure cap 7 is then inserted over the cork and the neck of the bottle in the manner best suited for the particular type of closure used.

The split ring 9, which has been sufficiently spread apart to allow it to clear the widest part of the bottle neck is then placed in position on the bottle neck and squeezed by a plier or other instrument into position in the groove so that the open ends of the steel band fit into the small recesses beneath the slab of glass 6 and close up to the sides of the partition of glass 5 directly behind the slab portion 6. The ring is squeezed 5 sufficiently tight in place so that it tightly wedges the portion of the closure cap in the groove against the inner wall of the groove 2 thereby 10 permanently maintaining that portion of the closure in place on the bottle and preventing anyone from mounting a new closure cap on the 15 bottle. It will be thus seen that the above described arrangement provides the bottle with a double seal which will prevent anyone tampering with the contents of the bottle since it is exceedingly difficult and impractical to remove the 20 permanent seal or ring 9 to place a new destructible seal or closure on the bottle and that portion of the closure which is permanently maintained in the external groove by the ring 9 will serve 25 as notice to the customer that the bottle originally was provided with a destructible seal and that the contents thereof had been tampered with.

30 To open the bottle all one has to do is to tear off the upper portion of the closure cap 7, the annular scoring 8 directly above the steel band 9 facilitating this operation. The cork 14 may then be taken out and replaced at will. However, while the upper portion of the closure cap 35 7 has been destroyed, the remainder of the closure stays lodged in the groove 2, being held permanently therein by the steel ring 2 which wedges it tightly up against the inner wall of the groove. As the steel ring can never be removed or taken off, a new closure cap cannot be put on the bottle and as the bottle, by reason of this condition, cannot be recapped, it is rendered useless to anyone who wishes to insert spurious products in such bottle for sale to the public and must be thrown away.

In a modified form of the invention, as shown in Figs. 4, 5 and 6, the glass partition 5 and the slab or knob of glass 6 of the preferred form of the invention may be omitted so that the groove 20 is continuous about the neck of the bottle. In the modified construction illustrated, the ring 21 consists of two pieces, the ends of which are welded together. The abutting ends of the two pieces are shaped in any suitable manner, as clearly shown in Fig. 4, to facilitate the welding of the pieces into a solid annular band which will fit snugly and tightly in the annular groove 20. It is, of course, understood that the ring 21 may be made in one piece as is ring 9 and mounted in the annular groove 20 in the same manner as is the ring 9, the ends however being welded together when the ring is in position in such groove to form a solid annular band. The outer edges of the ring 21 and the edges of the beads 22 and 23 which form the groove 20 are also suitably shaped as in the preferred form of the invention, to prevent anyone from removing the ring from the groove by means of a chisel or other sharp tool.

70 The neck 24 of the bottle in Figs. 4 and 5 is shown provided with a screw thread 25 upon which is screwed the metal cap or cover 26. The closure cap 7 is inserted over the cap 7 and anchored in the groove 20 by means of the ring 75 21 in the same manner as the preferred construc-

tion. It is of course obvious that any of the conventional types of corks or caps may be used for closing the bottle.

While I have shown and described the ring 9 in the preferred form of the invention as being made of one piece, it is obvious that it may consist of two pieces as in the modified construction, one end of each piece being welded together when the parts are placed in the groove to provide a single piece. I may also make the rings 9 and 21 of more than two pieces provided with suitably shaped ends so that they can be readily and strongly welded together on the bottles. I have also found that I obtain a ring of sufficient strength for the purposes of the invention by providing the ends of the pieces with oppositely disposed grooves or depressions and wedging a connecting piece in such oppositely disposed grooves or depressions by force.

The closure cap 7 may of course be made of 20 sheet metal, phenol plastic compounds or other suitable materials which will satisfactorily serve the purposes of the invention. The closure may be made so that the top portion will serve as the cover for the bottle after it has been separated from the lower portion or skirt of the closure cap, said portion being preferably provided with a thread which screws on the neck of the bottle. I may also make the closure of more than one piece which can be inserted in 30 place on the bottle before the sealing ring is placed in position.

The invention is also susceptible of other changes in the construction and arrangement of the parts without departing from the scope of 35 the appended claims and may be used to equal advantage in product containers made of a material other than glass.

The invention is of particular value for bottles or containers containing liquids, wines, beverages, perfumes, foodstuffs, pharmaceutical products, drugs, toilet preparations, remedies or other similar products. The permanently mounted bands of the invention are especially adapted to carry a trade-mark, code or manufacturer's or Government serial number, thereby making it extremely difficult to make imitation containers for fraudulent purposes. The construction of the sealing closure also makes it possible to affix Government stamps and seals on bottles or containers so that they won't come off. The stamps or seals may be attached to the bottle before a transparent closure cap and the steel band are put on the bottle or else placed over the cap in such manner that it is held in place by the steel band.

I claim:

1. In combination, a bottle having an external groove in the neck portion thereof, a destructible closure cap sealing the open end of said bottle and extending below said groove, a partition extending transversely of said groove, a covering element for said partition spanning said groove, said covering element being sufficiently wide to form a recess on each side of said partition, and a split ring surrounding a portion of said cap and positioned in said groove, the ends of said ring being positioned in the recesses formed on each side of said partition.

2. In combination, a bottle having an external groove in the neck portion thereof, a destructible closure cap sealing the open end of said bottle and extending below said groove, a partition extending transversely of said groove, a covering element spanning said groove and covering said partition, said covering element being sufficient- 75

ly wide to form a recess on each side of said partition, said bottle, partition and covering element being integrally formed, and a split metal ring surrounding a portion of said cap and positioned in said groove, the ends of said ring being positioned in the recesses formed on each side of said partition.

3. In combination, a bottle having an external groove in the neck portion thereof, a destructible closure cap sealing the open end of said bottle and extending below said groove, a partition extending transversely of said groove, a covering element spanning said groove and covering said partition, said covering element being sufficiently wide to form a recess on each side of said partition, said bottle, partition and covering element being integrally formed, and a split metal ring surrounding a portion of said cap and positioned in said groove, the open ends of said ring being positioned in the recesses formed on each side of said partition, said ring being of such diameter that it wedges the portion of said cap in said groove tightly against the inner wall thereof so as to maintain said portion of the cap permanently in said groove.

4. In combination, a container having a groove in the outer surface thereof, a closure cap sealing the open end of said container and extending below said groove, said cap being weakened by an annular scoring intermediate said groove and the open end of said container whereby that portion of the cap above the groove may be removed to open the container, and a band surrounding a portion of said cap and permanently positioned in said groove, said band being of such diameter that it wedges the portion of the cap in said groove tightly against the inner wall thereof so as to maintain said portion of the cap permanently in said groove.

5. In combination, a bottle having a closure cap over the open end thereof, a destructible sealing element sealing said closure cap on said bottle, an annular band encircling the neck of said bottle and surrounding a portion of said sealing element and adapted to prevent the substitution of another sealing element for the one on said bottle, said band being composed of relatively strong metallic material and having such rigidity of constitution and form that on application of prying pressure applied between the wall of the bottle, and the inner periphery of the band, the band will maintain its shape and position until the bottle is so deformed or destroyed as a result of the prying pressure as to be incapable of further use, and means for irremovably positioning said band on the bottle; said means being adapted to hold said band in non-rotatable relation with respect to said bottle in the sealed and unsealed condition of the latter.

6. In combination, a bottle having an external groove in the neck portion thereof, a closure for said bottle, a destructible sealing element sealing said closure on said bottle and extending below said groove, and a band covering a portion of said sealing element and positioned in said groove and adapted to cooperate with said groove to prevent the substitution of another sealing element for the one sealing said closure in the bottle, said band being composed of relatively strong material and having such rigidity of constitution and form that on application of prying pressure applied between the wall of the bottle and the inner periphery of the band, the band will maintain its groove-occupying shape and position until the bottle is so deformed or destroyed as

the result of the prying pressure as to be incapable of further use, and a stop positioned in said groove and adapted to cooperate with said band to prevent rotational movement of the latter in said groove.

7. The combination set forth in claim 6, including a permanently positioned covering element overlying the stop in said groove.

8. In combination, a container having an external groove positioned below the mouth thereof, a closure for said container, a double seal for said container, one of said seals comprising a destructible sealing element sealing said closure on the container and extending to a position below said groove, a portion of said sealing element lying in said groove, the second seal comprising a substantially heavy, indestructible and non-removable member positioned in said groove and sealing therein the portion of the first mentioned seal lying in said groove, so that said portion of the first mentioned seal remains beneath said second mentioned seal when the first mentioned seal is broken to remove the closure.

9. In combination, a container having an external groove positioned below the mouth thereof, a closure for said container, a double seal for said container, one of said seals comprising a destructible sealing element sealing said closure on the container and extending to a position below said groove, a portion of said sealing element lying in said groove, the second seal comprising a substantially heavy, indestructible and non-removable member positioned in said groove, said second sealing member having been applied over the portion of the first sealing member lying in said groove and having a close fit within said groove with respect to the interior wall thereof so that the insertion of a new first sealing member beneath said second sealing member is precluded.

10. In combination, a container having an external groove positioned below the mouth thereof, a closure for said container, a double seal for said container, one of said seals comprising a destructible sealing element sealing said closure on the container and extending to a position below said groove, a portion of said sealing element lying in said groove, the second sealing element comprising a substantially heavy, indestructible and non-removable metal band positioned in said groove and sealing therein the portion of the destructible sealing element lying in said groove so that said portion remains beneath said band when the destructible sealing element is broken to remove the closure, said band being so dimensioned with relation to said groove that the insertion of a new destructible sealing element beneath said band is precluded.

11. In combination, a container having a relatively deep external groove positioned below the mouth thereof, a closure for said container, a double seal for said container, one of said seals comprising a destructible sealing element sealing said closure on the container and extending to a position below said groove, a portion of said sealing element lying in said groove, the second sealing element comprising a band permanently positioned in said groove and overlying that portion of the destructible sealing element lying in said groove, said band being so dimensioned with relation to said groove that the insertion of a new destructible sealing element beneath said band is precluded and having such rigidity of constitution and form that on application of prying pressure applied between the wall of the container and the inner periphery of the band, the band will main-

tain its groove occupying shape and position until the container is so deformed or destroyed as the result of the prying pressure as to be incapable of further use.

5 12. A combination such as defined in claim 11, in which the band is composed of case-hardened metallic material.

13. A combination such as defined in claim 11, in which the band is composed of a plurality of

arcuately shaped pieces of metal welded together into the form of the band.

14. A combination such as refined in claim 11, in which the band comprises a plurality of elongated sections composed of metallic material and a plurality of metal elements connecting said sections together into the band form.

MURRAY KAY.
